UNITED STATES PATENT OFFICE.

CHARLES C. RUPRECHT, OF OLMSTED, ILLINOIS.

SCREENING MECHANISM.

Application filed May 4, 1922. Serial No. 558,421.

To all whom it may concern:

Be it known that I, CHARLES C. RUPRECHT, a citizen of the United States, residing at Olmsted, in the county of Pulaski and State of Illinois, have invented a certain new and useful Improvement in Screening Mechanism, of which the following is a full, clear, and exact description, reference being had to the accompanying drawings.

10 This invention relates to apparatus for screening materials and has for its general object to provide an apparatus of this character which is particularly efficient in operation, the construction and arrangement of 15 parts shown herein securing a very active screening action while securing and maintaining the distribution of the material over the screen. A further object of the invention is to provide a screen of this character 20 with an efficient means for operating the same electrically. Further and more limited objects of the invention will appear hereinafter and will be realized in and through the construction and arrangement of parts 25 described in the specification and embodied in the combinations of elements recited in the claims hereto annexed.

In the drawings, which show the present preferred embodiment of my invention, Fig.

30 Fig. 1 represents a front elevational view of a screening apparatus constructed in accordance with my invention; Fig. 2 a sectional elevation of such mechanism; Fig. 3 a sectional detail corresponding to the line 3—3 35 of Fig. 2; Fig. 4 a diagrammatic detail illustrating the action of the screen shown in the preceding views; Fig. 5 a view, similar to Fig. 3, showing a slight modification in the manner of mounting the movable portion of the screening mechanism; Fig. 6 a 40 view similar to Fig. 4, of a further modification; Fig. 7 a diagrammatic detail illustrating the action of the screening mechanism shown in Fig. 6; Fig. 8 a detail in sectional elevation of a modification of the screen mounting; and Fig. 9 a diagrammatic 45 illustration of the electrical means for operating the screen.

Describing by reference characters the 50 various parts illustrated herein, 1 denotes the inclined side rails, 2 the transverse bottom rail, and 3 the transverse top rail of a frame in which the screen proper is located. Projecting inwardly from each of 55 the rails 1 is a pair of lugs 4, one pair

being located near the top of each of the rails and the other pair being located near the bottom. Each pair of lugs supports a journal pin 5. Each pin has journaled thereupon the outer end of a link 6, the inner end of each of said links being journaled in like manner upon a pin 7 mounted in lugs 8 projecting outwardly from the side rails 9 of the screen proper. The side rails 9 are shown as extending within and parallel to the sides 1—1 and are connected by top and bottom cross rails 10 and 11, the upper cross rail being recessed, as indicated at 11^a, for the reception of the lower end of an intake chute 12, which may be conveniently mounted upon the cross rail 3 of the supporting frame.

To the bottoms of the longitudinal rails 9 and the cross rails 10 and 11 of the screen there is applied a wire mesh 13 constituting the active screening surface. The arrangement of the lugs 4 and 7 and the lengths of the links 6 are preferably such that the screen will be supported from its surrounding framework with the links normally extending both downwardly and inwardly, as shown in Fig. 3. The purpose and object of supporting the screen in this manner will be explained hereinafter.

For the purpose of agitating the screen, I preferably employ the electrical apparatus shown herein, said apparatus comprising an electromagnet 14 mounted in each of the side rails 1 of the supporting frame and each having its poles directed toward the adjacent side rail 9 of the screen. Each of the latter side rails is provided with an armature 15 whereby, by energizing the said magnets alternately, the screen will be oscillated laterally on its links 6.

For the purpose of oscillating the screen, each magnet may be energized in turn by an apparatus shown conventionally in Fig. 9, wherein 16 denotes a conductor leading from any source of electrical energy (as a main supply line) and electrically connected to the shaft 17 of a rotating contactor 18 having a segmental contact 19 which is electrically connected with the shaft 17. The segmental contact 19 is preferably 180° in extent. Current supplied to the conductor 16 will be delivered from the contact shaft 17 to the contact 19 and thence alternately to each of the magnets 14 by the wires 20 and 21 and from each of said magnets by means 110

of wires or conductors 22 and 23 back to the main line. The contacts 20^a and 21^a will be of sufficient width to lap slightly upon the contact segment 19, so that one magnet will cut in before the other is entirely cut off, thus obviating sparking.

Light helical springs 24 are preferably connected with the side rails 9 of the screen and are provided with adjusting stems 25 extending through the side rails 1 and provided with wing nuts 26. These springs tend to check and cushion the lateral movements of the screen.

Reference has been made hereinbefore to the manner of mounting the screen frame within the supporting frame. The preferred manner of mounting is shown in Figs. 3 and 4, wherein the width of the screen frame as compared with the width of its supporting frame is such that the lower ends of the links 6 project inwardly and preferably downwardly. When the screen is oscillated by energizing the magnets in conjunction with the rotating contactor, the movement imparted to the screen as the latter swings toward the right will cause the lifting of the left hand side of the screen and the depression of the right hand side thereof. When the screen moves in the opposite direction, the reverse action occurs; that is to say, the right hand side of the screen will be lifted and the left hand side lowered. There is practically no vertical movement of the central portion of the screen, as will be evident from Fig. 4. The action upon the material being screened is to keep the same distributed over the active screening surface while the up and down motion of each side of the screen tends to throw the material upwardly and to catch and hit the same as it falls. This results in a very effective screening action.

In Fig. 5 there is shown a modification of the manner of mounting the screen wherein the results obtained are substantially the same as those which are obtained by the mounting shown in Figs. 1-4 inclusive. In this view, the links 6 project inwardly from the side rails 1 but extend upwardly instead of downwardly. With this arrangement, it will be evident that rocking the screen to the left will result in raising the left hand side and lowering the right hand side instead of lowering the left hand side and raising the right hand side and that rocking the screen to the right will result in raising the right hand side and lowering the left hand side instead of lowering the right hand side and raising the left hand side. This, however, does not result in any different kind of action upon the material being screened.

In Figs. 6 and 7 there is shown a further modification of the manner of mounting the screen, wherein the pins 8 are normally in the same vertical plane with the correspond-

ing pins 5, instead of being located inwardly with respect to the last mentioned pins. This results in maintaining the screening surface horizontal throughout the entire range of movement of the screen. As the screen is moved to one side or the other from the position shown in Fig. 6, it is raised, but in a plane parallel with that which it occupied before. As is the case with Fig. 4, the full lines in Fig. 7 indicate the normal or inactive position of the screen while the dotted lines indicate the position which it occupies when oscillated upon its upper pivots 5.

In Fig. 8 there is shown a modification of the particular manner of mounting the screen illustrated in Figs. 1-4 inclusive. In this case, flat springs 27 are employed for the suspending links, the upper end of each spring being secured to its adjacent side rail 1 and the lower end being formed into an eye 28 which receives the appropriate pin 8 carried by the lugs 7.

In all forms of my invention I may use bumper blocks 29, preferably of rubber or similar yieldable material, to relieve the magnet poles from impact by the armatures 15; and in all forms except that shown in Figs. 6 and 7, the pivotal support for the outer end of each link is laterally offset from the pivotal support for the inner end.

Having thus described my invention, what I claim is:

1. An apparatus of the kind described comprising a rectangular supporting frame, a rectangular screen disposed within said frame in the same plane thereof, pivoted links connecting said screen at each end to said supporting frame, electric magnets on the side rails of said supporting frame between said links, armatures carried by said screen opposite said magnets, cushioning springs disposed between said screen and said frame to each side of said magnets and means for energizing and deenergizing said magnets for oscillating said screen.

2. An apparatus of the kind described comprising a rectangular supporting frame, a rectangular screen disposed within said frame in the same plane therof, pivoted links connecting said screen at each end to said supporting frame, the inner ends of said links being laterally offset from the outer ends thereof, electric magnets on the side rails of said supporting frame between said links, armatures carried by said screen opposite said magnets, cushioning springs disposed between said screen and said frame to each side of said magnets, means for adjusting the tension of said springs, and means for energizing and deenergizing said magnets for oscillating said screen.

3. An apparatus of the kind described comprising an inclined disposed supporting frame, a screen arranged within said frame

in the same plane thereof, pivoted links connecting said screen to said frame at each end and between the side rails thereof, centrally disposed armatures carried by said screen, 5 centrally disposed electric magnets carried by said frame, a cushioning spring disposed between said screen and said frame to each

side of said electric magnets and means for energizing and deenergizing said magnets alternately for oscillating said screen within 10 said frame.

In testimony whereof, I hereunto affix my signature.

CHARLES C. RUPRECHT.
